UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

DRAFT-GEAR.

1,343,295.

Specification of Letters Patent. Patented June 15, 1920.

Application filed September 7, 1915. Serial No. 49,225.

To all whom it may concern:

Be it known that I, HARRY F. WOERNLEY, a citizen of the United States, and resident of Pittsburgh, county of Allegheny, and State of Pennsylvania, have invented certain new and useful Improvements in Draft-Gears, of which the following is a specification, and which are illustrated in the accompanying drawings, forming a part thereof.

The invention relates to the type of draft gears shown in Patent No. 989,949, granted April 18, 1911, to Cotton and Henderson.

The object of the invention is to generally improve upon draft gears of this type, and particularly to provide, in connection with the maximum of friction resistance, an increased freedom of release after compression.

Minor advantages of the invention will appear in connection with a description of the embodiment thereof illustrated in the accompanying drawings, in which—

Figure 1 is a plan view of the device;

Fig. 2 is a sectional view on the line 2—2 of Fig. 1, and showing the device as applied to a railway car;

Fig. 3 is a detail plan view of the draft plates of a railway car showing the improved gear in central plan section, the parts being in normal position;

Fig. 4 is a view similar to Fig. 3, the gear being under compression and some of the parts which appear in section in Fig. 3 being shown in plan;

Figs. 5 and 6 are views in perspective of two forms of friction plates employed in the gear;

Fig. 7 is an end view of the gear;

Fig. 8 is a side view of the central wedging element with its retaining key; and

Fig. 9 is a detail transverse vertical section through the wedging elements.

The draft plates of a railway car are represented at 10, and as being provided with draft and buffing lugs 11, 12. The butt of the coupler is shown at 13, its extension or yoke is represented at 14 and as being of the loop type for inclosing the draft gear, its rear end being shown at 15.

The gear comprises a casing 16, one end of which, 17, may, as shown, constitute a follower for engaging the draft lugs 11. The opposite end of the casing 16 is open, and is faced by a follower plate 18 coöoperating

with the buffing lugs 12 and bearing against the end 15 of the yoke.

Housed within the casing 16 are a pair of nested springs 19, 20, the outer one 19 being the stronger. These springs are seated 60 against the closed end 17 of the casing. A central wedging element 21 is interposed between the inner end of the inner spring 20 and the follower plate 18. A pair of wedging elements 22, 23, laterally engage the element 21 and bear against the apertured follower plate 24, which is seated against the inner end of the outer spring 19, the wedging element 21 playing freely through its aperture. A key 25, set through the wedging 70 element 21, moves within a recess in the casing 16, the function of the key being to hold the parts in assembled position when the gear is not attached to the car. The outer faces of the wedging elements 22, 23, are 75 inclined inwardly toward the follower 24, this inclination being secured in the structure as represented by the contour of the coöoperating wedging faces of the several elements.

Located between the wedging elements 22, 23, and the side walls of the casing are two groups of friction plates, each composed of a plurality of plates 26, 27, 28, as many being employed as the space available and 85 judgment of the designer may dictate, and a plurality of plates 29, 30, 31, the members of the two sets being alternated. The plates 26, 27, 28, are anchored to the casing 16 against longitudinal movement, but are free 90 to move laterally. The engagement of these plates with the casing is through the medium of a pair of laterally projecting lugs 32, 33, which enter transverse recesses 34 in the casing walls and are thickened, as shown 95 at 35, to give them comparatively broad bearing faces against the margin of the apertures. The plates 29, 30, 31, are longer than the plates 26, 27, 28, and float within the casing, being movable both laterally and 100 longitudinally.

The plates 26, 27, 28, are wedge-shaped, their ends adjacent the follower plate 24 being the thicker for the purpose of increasing the wedging action to augment the friction.

Normally the parts occupy the position as shown in Fig. 3, the follower 17 being in engagement with the butt of the coupler 13 and with the draft lugs 11, the end of the 110

2
wedging element 21 being in engagement with the follower 18 and the latter bearing against the buffing lugs 12 and the yoke end 15. The follower 24 is held firmly against the wedging elements 22, 23, by the spring 19. The follower 24 is shown as bearing against the ends of the floating plates 29, 30 and 31, the latter, however, not reaching to the follower 18.

10 Under draft stresses the gear is compressed ultimately to the position shown in Fig. 4, the follower 18 being carried forward by the yoke, the wedging element 21 advancing against the resistance of the spring 20 and tending to spread the wedging elements 22, 23, thereby putting the friction plates under compression against the side walls of the casing. The coöperating wedging faces of the elements 21 and 22, 23, being quite abrupt, the relative longitudinal movement of the three elements is but slight and they are practically advanced together, moving the follower 24 away from the floating plates. These plates are presently engaged by the follower 18 and are advanced between the anchored friction plates. The three wedging elements 21, 22, 23, may be regarded as a single wedging unit, because of the inclined faces of the outer elements, 30 as may also each of the two groups of friction plates, and as the gear is compressed heavy lateral pressure is delivered to the friction plates by the combined action of these three wedging units.

35 Excessive wedging action by the elements 21, 22 and 23 is prevented by reason of the decided pitch of their contacting faces, there being a tendency under severe load for the outer elements in draft and for the inner element in buff to advance relatively to the coöperating element or elements, this tendency being resisted by the spring 19. While the inclination of the two groups of friction plates, with reference to the axis of the gear, is secured by reason of the tapering form of some of these plates, it is obvious that the action will be the same by whatever means such inclination is secured.

40 The friction is developed principally between the floating and the anchored plates, there being but slight relative movement of the elements 22, 23, and the adjacent floating plates.

45 Draft stresses are resisted primarily by the springs and secondarily by the friction between the several plates, and because of the wedge form of the combined wedging elements and of the two groups of friction plates sufficient friction is developed to 50 largely absorb such pressures even though very excessive, and thus protect the framing of the car. The gear reaches the limit of its compressive movement when the follower plate 18 comes into engagement with 55 the end of the casing 16.

Upon release due to the cessation of draft the spring 20 moves the wedging element 21 backwardly, and with it the follower plate 18 and the yoke 14, thus relieving the lateral pressure upon the elements 22, 23, which are 70 thereupon moved backwardly under the influence of the spring 19, in turn relieving the lateral pressure upon the friction plates. A violent recoil is, however, prevented because of the prompt action of the spring 19, 75 causing the elements 22, 23, to follow the element 21, with the result that the lateral pressure upon the friction plates is reduced gradually.

With the parts formed as shown the floating friction plates are slightly oblique to the axis of the gear. The pressure upon their ends by the plate 18 is, therefore, to some extent, lateral, thereby increasing their frictional engagement with the anchored plates. 80

Under the influence of buffing stresses the casing 16 is moved inwardly until it engages the follower plate 18. The action of the springs and wedging and friction elements is substantially the same as in draft, but in 90 reverse direction and order, the anchored plates moving, while the floating plates remain stationary after making contact with the rear follower. Upon release the casing is moved forwardly by the action of the spring 20. The excessive friction developed between the various friction faces will first cause all of the parts, except the central wedging element 21, to move forwardly together. The wedge faces of the elements 22, 23, sliding slightly on the wedge faces of the element 21, will reduce the lateral pressure, but this reduction is gradual because of the constant pressure of the spring 19. 100

While the action is quite similar to that of the gear shown in the Cotton and Henderson patent, a greater capacity is obtained and also a more certain release is secured under all circumstances.

Though the casing 16 is described as having a closed end against which the springs seat, it is obvious that as a seat for the springs any shoulder formed on the interior of the casing will serve the same purpose as the end wall. Various changes in details 115 can be made without departing from the scope of the invention.

I claim as my invention—

1. In a draft gear, in combination, a group of alternated friction plates, adjacent plates having relative longitudinal movement, the plates of one set being wedge-shaped, and means presenting a wedging face to the plates. 120

2. In a draft gear, in combination, a group of alternated friction plates, adjacent plates having relative longitudinal movement, the plates of one set being wedge-shaped, and wedging means presenting a wedging face to the plates and being longitudinally mov- 125 130

able with reference to the wedge-shaped plates.

3. In a draft gear, in combination, two groups of alternated friction plates, adjacent plates having relative longitudinal movement, the plates of one set in each group being wedge-shaped, and wedging means interposed between the two groups and presenting wedging faces thereto, the taper of such wedging means being the reverse of that of the wedge shaped plates.

4. In a draft gear, in combination, two groups of alternated friction plates, adjacent plates having relative longitudinal movement, the plates of one set in each group being wedge-shaped, and wedging means interposed between the two groups and presenting wedging faces thereto and being longitudinally movable with reference to the wedge-shaped plates.

5. In a draft gear, in combination, two groups of alternated friction plates, adjacent plates having relative longitudinal movement, the plates of one set of each group being wedge-shaped, and wedging means interposed between the two groups and presenting wedging faces thereto, such wedging means comprising a pair of outer members and a central member having wedging engagement therewith, and means for moving the central and the outer members of the wedging means in opposite directions.

6. In a draft gear, in combination, two groups of alternated friction plates, adjacent plates having relative longitudinal movement, the plates of one set of each group being wedge-shaped, and wedging means interposed between the two groups and presenting wedging faces thereto, such wedging means comprising a pair of outer members and a central member having wedging engagement therewith, and being longitudinally movable with reference to the wedge-shaped plates.

7. In a draft gear, in combination, two groups of alternated friction plates, adjacent plates having relative longitudinal movement, the plates of one set of each group being wedge-shaped, wedging means interposed between the two groups and presenting wedging faces thereto, such wedging means comprising a pair of outer members and a central member having wedging engagement therewith, and a pair of springs acting, respectively, on the outer and on the inner wedge members and urging them longitudinally in the same direction.

8. In a draft gear, in combination, two groups of alternated friction plates, adjacent plates having relative longitudinal movement, the plates of one set of each group being wedge-shaped, wedging means interposed between the two groups and presenting wedging faces thereto, such wedging means comprising a pair of outer members and a

central member having wedging engagement therewith, and being longitudinally movable with reference to the wedge-shaped plates, and a pair of springs acting, respectively, on the outer and on the inner wedge members 70 and urging them longitudinally in the same direction.

9. In a draft gear, in combination, a casing having a spring seat at one end and being open at the opposite end; a pair of springs 75 reacting against the seat, coöperating wedging elements acted upon, respectively, by the two springs, groups of friction plates interposed between the wedging elements and the walls of the casing, alternate plates of each 80 group being anchored against longitudinal movement relative to the casing and the remaining plates being longer than the anchored plates and having longitudinal movement with reference to the casing, alternate 85 plates of each group being wedge-shaped, the wedging elements having wedging engagement with the friction plates, a follower interposed between one of the springs and the longitudinally movable friction plates, 90 and a follower engaging one of the wedging elements and engageable with the movable friction plates.

10. In a draft gear, in combination, a casing having a spring seat at one end and being open at the opposite end, a pair of springs reacting against the seat, coöperating wedging elements acted upon, respectively, by the two springs, groups of friction plates interposed between the wedging elements and the walls of the casing, alternate 100 plates of each group being anchored against longitudinal movement relative to the casing and the remaining plates being longer than the anchored plates and having longitudinal 105 movement with reference to the casing, the anchored plates being wedge-shaped, the wedging elements having wedging engagement with the friction plates, a follower interposed between one of the springs and the 110 longitudinally movable friction plates, and a follower engaging one of the wedging elements and engageable with the movable friction plates.

11. In a draft gear, in combination, a 115 group of intercalated relatively movable flat friction plates, alternate plates being wedge-shaped, all of the plates being intersected by a single plane including the axis of the draft gear.

12. In a draft gear, in combination, two groups of intercalated relatively movable flat friction plates, alternate plates of each group being wedge-shaped, and a reversely directed wedge structure interposed between 125 the two groups, all of the plates being intersected by a single plane including the axis of the draft gear.

13. In a draft gear, in combination, two groups of intercalated relatively movable flat 130

friction plates, alternate plates of each group being wedge-shaped, and a reversely directed wedge structure interposed between the two groups, such structure comprising a 5 pair of shoes and an intermediate spreading element, all of the plates being intersected by a single plane including the axis of the draft gear.

14. In a draft gear, in combination, two 10 groups of intercalated relatively movable flat friction plates, alternate plates of each group being wedge-shaped, a reversely directed wedge structure interposed between the two groups, such structure comprising a pair of 15 shoes and an intermediate spreading element, and means for differentially moving the shoes and spreading element.

15. A draft gear, comprising in combination, a casing having parallel sides, two 20 groups of friction plates within the casing and each bearing against the sides thereof, alternate plates of each group being relatively fixed and movable, and one set thereof being wedge shaped, a wedging unit inter- 25 posed between the two groups and comprising a central member and two side members having wedging engagement therewith, the coöperating wedging faces of the members of the unit being more abrupt than the wedg- 30 ing faces of the members of the groups of plates, and followers bearing respectively upon one end of the central member of the

unit, and upon the opposite ends of the side members thereof.

16. A draft gear, comprising in combina- 35 tion, a casing having parallel sides, two groups of friction plates within the casing and each bearing against the side thereof, alternate plates of each group being relatively fixed and movable, and one set thereof 40 being wedge shaped, an expandible wedging unit interposed between the two groups and comprising a central and two side members in wedging engagement, and followers bearing longitudinally upon the unit and engaging respectively one end of the central member and the opposite ends of the side members. 45

17. A casing having side walls, a pair of plates longitudinally movable within the cas- 50 ing and the outer face of each having frictional engagement with an element longitudinally anchored to the casing, the adjacent faces of the plates being oblique to the axis of the casing and oppositely inclined, a 55 pair of plates each bearing against the inner face of one of the first named plates, and having inner faces inclined oppositely at a greater angle to the axis of the casing than the inclination of the inner faces of the first 60 named plates, and a complementary wedging element on the axis of the casing.

HARRY F. WOERNLEY.
